(57) **CLAIM**

The ornamental design for an outdoor light, as shown and described.

DESCRIPTION

FIG. 1 is a front, right side and top perspective view of an outdoor light showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front, right side and top perspective view of the outdoor light showing my new design with the mounting stake portion removed for illustrative purposes only; and, FIG. 9 is a front, right side and top perspective view of the diffuser portion of the outdoor light, the remaining sections being omitted for illustrative purposes only.
